UNITED STATES PATENT OFFICE.

WALTER W. CARPENTER, OF LANSDOWNE, PENNSYLVANIA.

CIRCUIT-BREAKING DEVICE.

1,254,477.

Specification of Letters Patent. Patented Jan. 22, 1918.

Application filed October 10, 1916. Serial No. 124,753.

To all whom it may concern:

Be it known that I, WALTER W. CARPENTER, a citizen of the United States, residing at Lansdowne, in the county of Delaware 5 and State of Pennsylvania, have invented certain new and useful Improvements in Circuit-Breaking Devices, of which the following is a specification.

My invention consists of an improved 10 circuit breaking device, and is particularly serviceable for use in connection with voltage regulators for electric generators.

It is a well known fact that in circuit 15 breaking devices which operate between the direct current and the alternate current magnets of high voltage regulators, the contacting members often fuse or stick together, and thereby cause delay in the breaking of the circuit. This causes an undesirable pulsating voltage, and often moves the alternating current solenoid plunger out of its proper position.

One object of my invention is to provide means which will compel the separation of 25 said contacting members at the proper time.

Another object is to make my invention of simple construction so that it can be manufactured and installed at a low cost.

These objects, and other advantageous 30 ends which will be described hereinafter, I attain in the following manner, reference being had to the accompanying drawings in which—

Figure 1 is a side elevation illustrating 35 direct current and alternating current controlled magnets having my improved circuit breaking device in connection therewith.

Figs. 2 and 3 are fragmentary elevations showing modified forms of my invention.

Referring to the drawings, 1 is the direct 40 current controlled magnet having a movable solenoid plunger 2, which is pivotally connected at 3 to a lever 4, the latter being fulcrumed at 5 on an arm 6 which is secured to the magnet 1.

The lever 4 has a comparatively rigid extension 7 having a hole 8 adjacent its free end, said hole forming a guide-way for an adjusting screw 9, the latter having a threaded portion 10 which engages a tapped opening 11 in a head 12, said head 12 being formed adjacent the outer end of a spring plate 13 which is secured to the under face of the lever 4 as clearly shown in Fig. 1.

The alternating current controlled mag- 55 net is shown at 14, the latter having a mov-

able solenoid plunger 15, the lower end of the latter being movable within a dash pot 16 in the usual manner in voltage regulators of the above described type.

The upper end of the plunger 15 is pivoted at 17 to a lever 18, the latter being fulcrumed at 19 on an arm 20 which is secured to the top of the magnet 14.

An adjusting screw 21 has a threaded portion 22 which fits within a tapped opening 23 adjacent the outer free end of the lever 18. The adjusting screws 9 and 21 are normally in axial alinement and have their ends 24 and 25 designed to contact with each other to complete an electric circuit between the levers 4 and 18.

In the operation of the device, the solenoid plunger 2 of the direct current controlled magnet 1 moves downwardly and consequently moves the end 26 of the lever 4 upwardly. This movement also effects an upward movement of the spring plate 13. However, if the contacting ends 24 and 25 of the screws 9 and 21 are fused or stuck together, the spring plate 13 owing to its thinness and length will bow or flex before the contact is broken and thus delay the breaking of the contact and cause the undesirable pulsating current above mentioned. In order to prevent this delay in the breaking of the contact, I provide an auxiliary 80 spring plate 27 which is spaced below the plate 13 and secured to the lever 4 as clearly shown in Fig. 1.

The free end 28 of this spring plate 27 as illustrated in Fig. 1, projects upwardly for a short distance and is positioned between the end of the lever 4 and the screw 9. It will thus be seen that with this construction, if the spring plate 13 flexes as above noted, the end 28 will after a slight movement, engage the lower surface of said plate 13 and thereby apply a force thereto at a point close to the screws 9 and 21 which will insure the breaking of the contact.

The length and thickness of the spring plate 27 may be varied to suit conditions. Furthermore, it will be noted that the action of the end 28 of the spring plate 27 does not only provide a constant pressure, but actually gives a slight tapping movement which insures the breaking of the contact and tends to drag the screw 9 out of its alined position with the screw 21, thereby not creating a direct upward pull which would lift the outer end of the lever 18.

which might disturb the position of the solenoid plunger 15.

In Fig. 2, I have shown another form of auxiliary plate spring as indicated at 29, 5 and instead of having the free end turned upwardly as shown in Fig. 1, I form a ridge or projection 30 which extends upwardly adjacent the free end of said spring plate 29.

In Fig. 3, the auxiliary plate is flat 10 throughout its entire length as shown at 31 and depends upon the direct engagement of its free end 32 to accomplish the purpose as above described. In all other respects the constructions shown in Figs. 2 and 3 are 15 similar to those illustrated in connection with Fig. 1, and I have therefore given the same like reference numerals.

My invention is of great value in the art 20 and is of particular value when used in connection with voltage regulators for generators; however it may be used in connection with any circuit breaking device which has elements corresponding to those above described.

25 While I have described my invention as taking a particular form, it will be understood that the various parts of my invention may be changed without departing from the spirit thereof, and hence I do not limit 30 myself to the precise construction set forth, but consider that I am at liberty to make such changes and alterations as fairly come within the scope of the appended claims.

Having thus described my invention, what 35 I claim as new and desire to secure by Letters Patent is:

1. The combination in a circuit breaking device including two contacting members, 40 of members forming supports for said contacting members, one of said members being elongated and comparatively flexible, a rigid lever secured to said latter member at a position remote from its contact member, means for moving said lever, an elongated 45 auxiliary member throughout its entire length being spaced from and having a portion designed to be moved into engagement with said latter mentioned member at a position between its connection with said lever

and its contact member whereby the separation of the contact members is assured after the lever is moved, substantially as described.

2. The combination in a circuit breaking device including two contacting members, 55 of members forming supports for said contacting members, one of said members being elongated and comparatively flexible, a rigid lever secured to said latter member at a position remote from its contact member, 60 means for pivotally moving said lever, and a resilient elongated auxiliary member connected to said lever and throughout its entire length being normally spaced from and having a portion designed to be moved into 65 engagement with said latter mentioned member at a position between its connection with said lever and its contact member whereby the separation of the contact members is assured when the lever is moved, substantially as described.

3. The combination in a circuit breaking device including two contacting members, 75 of members forming supports for said contacting members, one of said support members being elongated and comparatively flexible, a rigid lever secured to said latter member at a position remote from its contact member, means for pivotally moving said 80 lever, an auxiliary member connected to said lever and having an elongated portion which throughout its entire length is normally spaced from said latter mentioned member, 85 said portion also having a projection extending toward said latter mentioned support member designed to be moved into engagement therewith at a position between its connection with said lever and its contact member whereby the separation of the 90 contacting members is assured when the lever is moved, substantially as described.

In testimony whereof I have signed my name to this specification in the presence of two subscribing witnesses.

WALTER W. CARPENTER.
